CONTROLLING MEANS FOR BATCH OPERATING MACHINES

Clifford R. Dumble, Arlington Heights, Mass., assignee, by mesne assignments, to California Process Company, Los Angeles, Calif., a corporation of Nevada

Application November 4, 1935, Serial No. 48,235

9 Claims. (Cl. 161—1)

This invention relates to means for controlling the time required for a cycle of operation of machines designed to operate upon batches of materials, such as so-called "dusters", fibre cleaning machines, stock washing machines, and the like. Such "batch" machines are usually provided with means for feeding material into a chamber wherein it is operated upon for a desired length of time and then discharged; then a fresh batch of material is fed in and the cycle repeated. In such machines it is frequently necessary or desirable to vary the time of actual treatment of the batch of material, according to the kind or quality thereof.

15 The object of my invention is to provide novel electric timing means whereby the length of time required for feeding material into the operating chamber may be kept uniform; and also the time required for discharging the material from the operating chamber may be kept uniform; but 20 the time required for operating upon a batch of material (i. e., the time between the feeding and discharging operations) may be increased or diminished in accordance with the kind or quality of the material being treated.

25 My invention provides novel means including light sensitive devices controlling the electric circuits operating the electro-mechanical devices for feeding material into the chamber; and also the circuits operating the electro-mechanical 30 means for discharging the material from the chamber.

To accomplish this object I have invented novel electro-mechanical control means, illustrated in the accompanying drawing, which I will explain 35 with reference thereto; and set forth in the claims the novel features, and novel constructions and combinations of parts, for which protection is desired.

40 In said drawing:—

Fig. 1 is a diagrammatic view illustrating my novel controlling mechanism in connection with a batch "duster" of the type referred to; and

Fig. 2 is a view of one of the disks, detached.

45 As shown in the drawing, my timer includes a movable member or disk 1 moving between lights such as 2 and 3 and related light sensitive devices such as phototubes 4 and 5; which are respectively connected to relays 27 and 40 connected in circuit with the feed mechanism and the discharge door mechanism of the batch machine in connection with which the invention is employed.

50 The disk 1 may be rotated at uniform speed by any suitable mechanism. As shown it is de-

tachably mounted upon a shaft 6a driven by speed reducing gearing 6 from a motor 7. One terminal of motor 7 is connected by wire 18 to the lead 12 of the power input; and the other terminal is connected by wire 13 to the lead 12a of said input.

5 Disk 1 may have one or more groups of perforations or slots 1a, 1b, the perforations in each group being disposed on different pitch circles. The rays from lights 2 and 3 respectively pass 10 through the related perforations to the related phototubes 4 and 5. The rays of light before passing through said perforations are preferably brought to a focus in the plane of the disk by means of double plano-convex condensing lenses 15 3 and 9 interposed between the lights and the disk.

Light 2 is connected by wires 14, 15 to a step-down transformer 16; and lamp 3 connected by wires 17, 18 to a step-down transformer 19. The primary voltages of the transformers may be controlled by a "General Radio Variac" 20 connected by wires 21, 22 to the leads 12, 12a. Such "Variac" is fully shown and described in U. S. Letters Patent No. 2,009,013, dated July 23, 1935, 25 and needs no further description herein. The primaries of the said transformers are connected to variac 20 by wires 23, 24.

30 The light sensitive device or phototube 4 is connected by wires 25, 26 to the switch coil 27a of a relay 27, the main switch coil 27b of which is in circuit with the contacts of switch coil 27a and connected by wires 28, 29 to the input leads 12, 12a. When coil 27a is energized by phototube 4 the normally open switch contacts will be 35 closed to complete the circuit from the leads 12, 12a to the main switch coil 27b, thereby closing the normally open relay switch 27c, one side of which is connected by wire 30 directly to one lead 31 of a solenoid W controlling the discharge operating devices. The other side of switch 27c is connected by wire 32 to the power lead 12; and lead 12a is directly connected to a wire 33 having a branch 33a connected to the other lead 31a of 40 said solenoid.

45 A pilot lamp 34 is connected by wires 35, 36, 37 across the wire 30 and lead 12a; and when lamp 34 fails to light it signifies that lamp 2 has burned out, or that phototube circuit is not working.

50 In the example shown, a second light sensitive device or phototube 5 is connected by wires 38, 39 to the coil 40a of a normally open switch the contacts of which are in circuit with the main switch coil 40b of a relay 40. Coil 40b is con- 55

- nected by wires 28, 29 to the power leads 12, 12a. Switch 40c of relay 40 is normally open, but closes when coil 40b is energized. One side of switch 40c is connected by wire 42 to one lead 5 43 of a motor M which operates the feed mechanism. The other side of switch 40c is connected by wire 41 to the power lead 12. The other lead 10 43a of motor M is connected through wires 33b and 33 to the power lead 12a. When switch 40c is closed motor M will be energized. Preferably 15 a so-called "Arrow" connector and plug 31p is inserted between the leads 30, 31 and 33a, 31a, and a similar "Arrow" connection 43p is inserted between the leads 33b—43a and 42—43. Such 20 connectors are made by the Arrow Electric Co., of Hartford, Connecticut, and are not essentials of the invention, but simply afford a simple means for opening the circuits in case repairs are necessary.
- 20 The relays 27 and 40 are preferably of the "LE" type, manufactured by Westinghouse Electric Mfg. Co., but the particular construction of such relays is not a feature of the present invention.
- 25 A pilot lamp 44 is connected by wires 37, 45, 49 across the wire 42 and lead 12a and if lamp 43 fails to light it signifies that lamp 3 has burned out, or that phototube circuit is not working. Preferably the lamps 2 and 3 are provided with 30 two filaments, the second one being merely a spare; only one filament is used at a time and the second filament is used only when the first burns out.

35 Fig. 1 diagrammatically illustrates the electrical connections between my novel timing devices aforesaid and the machine to be controlled thereby. For convenience, and to facilitate an understanding of the operation, I will describe the connections between the timer and a "Duster" 40 of the type shown in the copending application of Brown et al., Serial No. 713,062, filed February 26, 1934, Patent No. 2,036,915 of April 7, 1936.

45 The "duster", indicated in Fig. 1, comprises a rotary beater A mounted in a chamber B partially surrounded by screens C. The beater A may be rotated continuously at uniform speed by any suitable means. As shown it is driven by a belt J from a motor K. Material is fed into chamber 50 B by a conveyor D and feed rolls E. One feed roll E may be driven by a belt L from motor M. Material may be discharged from the chamber through an opening normally closed by a door F mounted on a rock shaft G; and the door F 55 may be opened and closed by means of a pitman I connected to an arm H on rock shaft G and to a piston N in a cylinder O, to which air, or other fluid, may be admitted through pipes P or Q from a pipe X connected to a suitable fluid supply. The admission of fluid to cylinder O is controlled by a valve R, in a casing S, said valve having a stem T normally held down by contractile springs U. Stem T is connected to the core of solenoid W. When the solenoid is excited 60 valve R will be raised and the air or fluid will be admitted into the upper end of cylinder O and depress the piston N thereby opening door F.

65 In such duster a batch of material is fed into the chamber B by conveyor D, and after it has been sufficiently operated upon by beater A the discharge door F is opened and the material discharged; then door F is closed; then a fresh batch of material is fed in by the conveyor D; and the aforesaid cycle of operations repeated.

Operation

The several operations of feeding material to the operating chamber; the length of time the material is operated on in the chamber; and the discharge of material from the chamber, are 5 controlled by my invention as follows:—

The holes 1a, 1b of each group in disk 1 (see Fig. 2) are shown as spaced about 192° apart; but this angularity can be altered if desired. The outer hole 1a controls the opening and closing of 10 the discharge door F, and the inner hole 1b controls the operation of the feed conveyor motor M.

When switch 11 in power lead 12 is closed, the circuit to motor 7 will be completed, and disk 1 15 will be rotated in the direction of the arrow (Fig. 2); and lamps 2 and 3 will be lighted.

Each time a perforation 1a in the disk registers with the ray of light from lamp 2, the phototube 4 will be excited and the coil 27a of relay 27 will close the circuit to the main coil 27b, and switch 27c will be closed, thereby completing the circuit from the power leads 12, 12a through the solenoid W; and this circuit will remain closed as long as the perforation 1a permits light rays from lamp 2 to reach the phototube 4. When solenoid 25 W is energized valve R will be raised and the discharge door F of the duster will be opened as above described. When perforation 1a passes out of register with the beam of light from lamp 2, switch 27c will automatically open, thereby opening the circuit to solenoid W whereupon valve R will be depressed by the springs U permitting air to pass into the lower end of cylinder O and raise the piston N and close the discharge 30 door F.

Thereafter the perforation 1b in the disk will register with the beam of light from lamp 3 and phototube 5 will be excited; and switch coil 40a of relay 40 will be closed whereupon the main coil 40b will be excited and close switch 40c, 40 which closes the circuit to motor M, as above described, and the feed conveyor will be operated as long as perforation 1b permits passage of rays of light from lamp 3. When perforation 1b passes out of register with the rays of light from lamp 3 the circuit to coil 40a of relay 40 will be opened, and switch 40c will automatically open; whereupon motor M will stop and the feed of material arrested. Assuming the rotation is as shown, a hole 1a will start the door, and 12° later a hole 50 1b will start the conveyor. In such case the two holes would be 192° apart. Lights 2 and 3 are placed on the same horizontal plane, but on different radii. If phototube 4 fails to operate, relay 27 is inoperative, and therefore, the circuit through 34 and 44 will not close. This also applies if either lights 2 or 3 burn out. The lamps 34 and 44 could burn out and still the apparatus function, but when the lamp goes out it indicates 55 that something is wrong.

60 The time for a complete duster cycle of operations can be readily computed according to the speed of rotation of disk 1, and the number of groups of holes 1a, 1b therein. To obtain the actual processing time (i. e., the action on the material by the beater) it is necessary to deduct from the cycle the time intervals required for opening and closing the door F, and for operating the feed conveyor D, which time intervals are 70 controlled by the size of the perforations or slots 1a, 1b respectively. The time interval between the door closing operation and the operation of the feed conveyor is controlled by the angle between the holes 1a and 1b in each group. This 75

angle is shown as approximately 192° in Fig. 2, but can be altered as desired.

While disk 1 may be provided with any desired number of groups of perforations or slots 1a, 1b, I prefer to provide a number of interchangeable disks respectively having from 4 to 16 such groups of perforations, and marked with the actual processing time in hundredths of a minute, so that the operator may readily select and use that disk 10 having the desired number and arrangement of groups.

The size of the holes or slots in the timing disks, and the relation between the length of time that the door is open and the time it is closed, and the length of time that the feed conveyor is operated, and the intervals between the closing of the door and the starting of the conveyor, are controlled by the size of the holes and the distance between them.

20 I have described the relay circuits controlled by the phototubes, as being energized or closed when the light beams pass through the perforations in the moving member or disk 1; and as described the phototubes are normally dark and the relay circuits are closed only when a light beam passes through a hole or perforation in the moving member 1 and illuminates the related phototube. But the parts could be so arranged that the relays would be closed when the phototubes are dark 30 and opened when the phototubes are illuminated.

While I have described my invention as used in connection with a "duster", it is applicable to other kinds and types of machines working upon batches of material, and is not limited to 35 dusters. Further, while I have described the invention as having a separate motor for driving disk 1, I do not consider the invention restricted to such a drive; for said disk could be driven by clock mechanism, or in some instances could be 40 driven if desired from the beater shaft, or main shaft of the machine with which my controlling apparatus is employed.

Also while I have illustrated the invention as having two phototube light circuits, I do not consider the invention limited to this number, as in 45 some cases one could be used; and in other cases more could be employed according to the number of circuits it is desired to control. Further, while I have described the control member as a 50 rotatable disk, which is a most convenient form, obviously a perforated slide could be used with proper means to move the same between the lamps and the phototubes.

I claim:—

55 1. In combination with a batch processing machine having a feed and a delivery, an electrically controlled means for operating the feed, and an independent electrically controlled means for operating the delivery; of a timing mechanism for controlling the processing of batches in continuous succession comprising a movable member having holes, one hole for controlling the delivery means, and the other hole for controlling the feed means; a plurality of means for focusing light beams at one side of the member in the path of the respective holes; a plurality of phototubes at the other side of the member each disposed to respond to light passing through the hole with which it is associated; an electric circuit controlled by one phototube for actuating the delivery control means; and another electric circuit controlled by the other phototube for actuating the feed control means; the time during which the delivery means is actuated and the 70 time during which the feed means is actuated 75

being determined by the speed of movement of the member and the size of the holes.

2. In combination with a batch processing machine having a feed and a delivery, a normally open electric circuit including means for operating the feed, and an independent normally open electric circuit including electrically controlled means for operating the delivery; of a timing mechanism controlling the processing of batches in continuous succession comprising a movable member having a group of holes, a plurality of means for focusing light beams at one side of the member in the path of the respective holes; a plurality of phototubes at the other side of the member each disposed to respond to light passing through the hole with which it is associated; a primary electric circuit controlled by one phototube for closing the normally open delivery operating circuit, and another primary electric circuit controlled by the other phototube for closing the normally open feed control circuit, the time during which the delivery circuit is closed and the time during which the feed circuit is closed being determined by the speed of movement of the member and the size of the holes. 20 25

3. In combination with a batch processing machine having a feed and a delivery; an electrically controlled means for operating the feed, and an independent electrically controlled means for operating the delivery; of a timing mechanism controlling the processing of batches in continuous succession comprising a movable member; a plurality of phototubes on one side of said member, one phototube being connected to operate said feed operating means and another phototube 30 connected to operate said delivery operating means; a plurality of light sources on the opposite side of said member corresponding with said phototubes; said movable member containing a plurality of groups of holes, each group including a hole for transmitting light to the feed operating phototube, and a hole for transmitting light to said delivery operating phototube. 35 40

4. In combination with a batch processing machine having a feed and a delivery, an electrically controlled means for operating the feed, and an independent electrically controlled means for operating the delivery; of a timing mechanism for controlling the processing of batches in continuous succession comprising a movable member; a plurality of phototubes on one side of said member, one phototube being connected to operate said feed operating means and another phototube connected to operate said delivery operating means; a plurality of light sources on the opposite side of said member corresponding with said phototubes; said movable member containing a plurality of groups of holes, each group including a hole for transmitting light to the feed operating phototube, and a hole for transmitting light to said delivery operating phototube; the time between the end of the feed operation and beginning of the delivery operation being determined by the speed of the member and the distance between the feed controlling hole of one group and delivery controlling hole of the next adjacent group along the line of movement of the movable member. 50 55 60 65

5. In combination with a batch processing machine having a feed and a delivery, an electrically controlled means for operating the feed, and an independent electrically controlled means for operating the delivery; of a timing mechanism for controlling the processing of batches in continuous succession comprising a movable member; a plurality of phototubes on one side of said 70 75

- member, one phototube being connected to operate said feed operating means and another phototube connected to operate said delivery operating means; a plurality of light sources on the opposite side of said member corresponding with said phototubes; said movable member containing a plurality of groups of holes, each group including a hole for transmitting light to the feed operating phototube, and a hole for transmitting light to said delivery operating phototube; the time during which the delivery circuit is closed and the time during which the feed circuit is closed being determined by the speed of movement of the member and the size of the holes, and the time interval between the delivery and the feed being determined by the difference between the distances of the holes in each group along the line of movement of the movable member from their respective light foci.
6. In combination with a batch processing machine having a feed and a delivery, an electrically controlled means for operating the feed, and an independent electrically controlled means for operating the delivery; of a timing mechanism for controlling the processing of batches in continuous succession, comprising a movable member; a plurality of phototubes on one side of said member, one phototube being connected to operate said feed operating means and another phototube connected to operate said delivery operating means; a plurality of light sources on the opposite side of said member corresponding with said phototubes; said movable member containing a plurality of groups of holes, each group including a hole for transmitting light to the feed operating phototube, and a hole for transmitting light to said delivery operating phototube; the time during which the delivery circuit is closed and the time during which the feed circuit is closed being determined by the speed of movement of the member and the size of the holes; the time interval between delivery and feed being determined by the difference between distances of the holes in each group along the line of movement of the movable member from their respective light foci; and the time between the end of the feed operation and beginning of the discharge operation being determined by the speed of movement of the member and the distance between the feed controlling holes of one group and the delivery controlling hole of the next adjacent group along the line of movement of the movable member.
7. In combination with a batch processing machine having a feed and a delivery, an electrically controlled means for operating the feed, and an independent electrically controlled means for operating the delivery; of a timing mechanism for controlling the processing of batches in continuous succession comprising a rotatable disk; a plurality of phototubes at one side of the disk, one phototube being connected to operate said feed operating means, and another phototube connected to operate said delivery operating means; a plurality of light sources on the opposite side of said disk corresponding with said phototubes, said disk containing a plurality of groups of holes, each group including a hole for transmitting light to the feed controlling phototube and a hole for transmitting light to said delivery controlling phototube; the time during which the delivery circuit is closed and the time during which the feed circuit is closed being determined by the speed of rotation of the disk

and the size of the holes; the time interval between delivery and feed caused by each group of holes being determined by the difference between the distances of the holes in each group in the direction of rotation of the disk from their respective light foci; and the time between the end of the feed operation and beginning of the discharge operation caused by the groups of holes being determined by the speed of rotation of the disk and the distance between the feed controlling hole of one group and the delivery controlling hole of the next adjacent group in the direction of rotation of the disk.

8. In combination with a batch processing machine having a feed and a delivery, a normally open electric circuit including means for operating the feed, and an independent normally open electric circuit including electrically controlled means for operating the delivery; of a timing mechanism for controlling the processing of batches in continuous succession comprising a movable member; a plurality of phototubes on one side of said member, one phototube being connected to operate said feed operating means and another phototube connected to operate said delivery operating means; a plurality of light sources on the opposite side of said member corresponding with said phototubes; said movable member containing a plurality of groups of holes, each group including a hole for transmitting light to the feed operating phototube, and a hole for transmitting light to said delivery operating phototube; a primary electric circuit controlled by one phototube for closing the normally open delivery operating circuit; and another primary electric circuit controlled by the other phototube for closing the normally open feed control circuit, the time during which the delivery circuit is closed and the time during which the feed circuit is closed being determined by the movement of the member and the size of the holes; and the time between the end of the feed operation and beginning of the discharge operation caused by the groups of holes being determined by the movement of the member and the distance between the feed controlling hole of one group and the delivery controlling hole of the next adjacent group along the direction of movement of the member.

9. In combination with a batch processing machine having a feed and a delivery, a normally open electric circuit including means for operating the feed, and an independent normally open electric circuit including electrically controlled means for operating the delivery; of a timing mechanism for controlling the processing of batches in continuous succession, comprising a movable member; a plurality of phototubes on one side of said member, one phototube being connected to operate said feed operating means and another phototube connected to operate said delivery operating means; a plurality of light sources on the opposite side of said member corresponding with said phototubes; said movable member containing a plurality of groups of holes, each group including a hole for transmitting light to the feed operating phototube, and a hole for transmitting light to said delivery operating phototube; a primary electric circuit controlled by one phototube for closing the normally open delivery operating circuit, and another primary electric circuit controlled by the other phototube for closing the normally open feed control circuit, the time during which the delivery circuit

is closed and the time during which the feed circuit is closed being determined by the movement of the member and the size of the holes; the time interval between delivery and feed caused by the holes of each group being determined by the difference between the distances of the holes in each group in the direction of movement of the member from their respective light foci; and the time between the end of the feed operation

and beginning of the discharge operation caused by the groups of holes being determined by the movement of the member and the distance between the feed controlling hole of one group and the delivery controlling hole of the next adjacent group along the direction of movement of the member. 5

CLIFFORD R. DUMBLE.
